UNITED STATES PATENT OFFICE

2,495,450

MUSICAL TONE MODIFIER

William D. Gladstone, New York, N. Y.

Application July 25, 1946, Serial No. 686,086

2 Claims. (Cl. 84—411)

1

My invention relates to tone modifiers for drums, and refers particularly to tone modifiers adapted for modifying the tones of percussion musical instruments, such as base drums having two vibratory heads in the absence of snares.

The necessity of accurate timing of base drums, and similar percussion musical instruments, especially for use in orchestral arrangements, is well recognized.

It is also well known that in instruments of this character, the lower vibratory head should give the same tonal effect as the upper, or batter, head, when the latter is caused to vibrate by the percussion of an instrument thereon.

In stretching a drum head over the body of a drum and affixing it thereto by the generally employed means, it is impossible to stretch it so as to obtain an accurate desired tonal effect, and the tonal effect thus produced is positive and cannot be changed except by some additional devices so constructed as to allow of a number of different tonal effects in order to produce the correct one as desired for different musical scores.

My invention, therefore, is directed to devices adapted to modify the tonal effect of such percussion instruments to produce a desired tonal effect and to maintain it during the continued use of the instrument.

The effectiveness and utility of the devices of my invention will be evident upon a consideration of my specification and its accompanying drawings.

Figure 1 is a section through the line 1—1 of Figure 2 of one form of a device of my invention.

Figure 2 is a section through the line 2—2 of Figure 1.

Figure 3 is a fragmentary outside view of Figure 1.

The particular form of a device of my invention shown in the accompanying drawings comprises a drum having the side 10, the vibratory batter head 11 and the lower vibratory head 12, said heads being attached to side members by any suitable means.

A revolvable shaft 13 passes through the side 10, and has a handle 14 fixedly attached to its outer end portion, a downwardly extended cord-attaching member 15 having the extended stud 16 is fixedly attached to the shaft 13 and revolves therewith, a downwardly extended member 17 is pivotally carried by the stud 16 of the member 15.

An elongated plate 18 is fixedly attached to the inner face of the drum side 10, and has the in-

wardly extended end portions 19 and 20. A grooved idler 21 is attached to the extended member 19 and a lower grooved idler 22 is attached to the extended member 20.

An elongated resilient modifier-carrying member 23 is fixedly attached to the extended member 19 and a similar elongated resilient member 24 is attached to the extended member 20. An elongated member 25 is fixedly attached to the member 23, and a similar extended member 26 is fixedly attached to the member 24, these members 25 and 26 being positioned at right angles to the members 23 and 24 respectively.

Each extreme portion of the member 25 carries a fixedly attached tone modifier 27 formed of rubber in a cup-shaped form, and each extreme portion of the member 26 carries a similar tone modifier 28.

A grooved idler 29 is carried by the inner end portion of the member 23 and a similar grooved idler 30 is carried by the inner end portion of the member 24.

An inwardly extended plate 31 is fixedly attached to the member 18. A revolvable shaft 32 passes through an opening in the plate 31, and carries a fixedly attached cog wheel 33 upon one side of the plate 31. The other end portion of the shaft 32 carries the fixedly attached member 34 having the two extended radial arms 35 and 36. A revolvable shaft 37 passes through the side 10 and is supported by brackets 38—38, the inward portion of the shaft 37 carries a worm gear 39 with the cog wheel 33. It will thus be noted that the revolution of the shaft 37 will revolve shaft 32, cog wheel 33 and the member 34.

The outer end portion of the shaft 32 passes through a plate 40 attached to the outer face of the side 10 and having graduating designations thereon, the extreme outer end of the shaft 32 carrying a fixedly attached finger piece 41 having an extended pointer portion 42.

One end of a cord, or wire, A is fixedly attached to the member 17, passes over the idler 22 and over the idler 29, and the end thereof fixedly attached to the arm 36.

One end of another cord, or wire, B, is fixedly attached to the member 17, passes over the idler 22, over the idler 21, over the idler 30 and the end thereof fixedly attached to the arm 35.

It will thus be seen that when the device is in the condition shown in the drawings, with the handle 14 in an upright position, the wire modifiers 27—27 will be firmly pressed against the batter head 11 and the modifiers 28—28 will be firmly pressed against the bottom head 12, due to the

resiliency of the members 23 and 24. If the handle 14 is revolved to a lower position, the movement of the member 17 and its actuated cord A will pull the tone modifiers in the direction of the arrows inwardly and away from the heads 11 and 12, until the handle 14 is in a perpendicular position when the resiliency of the members 23 and 24 will be overcome and the tone modifiers will be at rest in spaced relation to drum heads.

It will be noted that this described portion of my invention does not allow of any fixed pressure of the tone modifiers upon the drum heads, other than that caused by the resiliency of the members 23 and 24.

It is frequently highly desirable that a drum should be so constructed that any tonal effect from heavy muffling, as indicated in the drawings, to no muffling may be maintained during the use of the device and the devices described in my specification accomplish this desired result.

If the knob 41 is revolved the movement of the member 17 and its actuated cord B will pull the tone modifiers in the direction of the arrows inwardly and away from the heads 11 and 12. It will be noted that this movement of the knob 41, and consequently the pressure of the tone modifiers upon the heads, may be stopped at any desired point and that the tone modifiers will remain in such fixed position, due to the worm gear mechanism.

In operation the heads of a drum are stretched and attached to the side of the drum by any satisfactory manner, during which operation the tone modifiers are completely spaced therefrom. The handle 14 is then turned to release the resiliency of the two members 23 and 24, thus causing all of the tone modifiers to be pressed strongly upon the inner sides of the heads and thus removing all overtones. The handle 41 is then turned slowly thus gradually decreasing the pressure of the tone modifiers upon the heads until the thus allowed overtones produce the desired pitch, the device being of such construction that this desired pitch is maintained during the use of the drum.

By the word "cord," I mean thread, cord, wire, chain or any other suitable means.

By the words "tone modifiers," I mean devices which may be cup-shaped, flat or of other physical shape, which may be composed of rubber, felt or other suitable material.

It will thus be seen that my invention presents devices whereby a desired pitch of tone can be obtained in drums and other similar percussion musical instruments, by varying the pressure of the tone modifiers upon the vibratory head of such instruments, and that the thus desired tone will be retained during the use of the instrument, and further, that the indicia upon the external dial will indicate exactly how various tone effects can be repeated.

I do not limit myself to the particular size, shape, number and arrangement of parts set forth in my specification as these can be varied without going beyond the scope of my invention.

What I claim is:

1. A percussion musical instrument provided with means for masking overtones to any desired extent, said instrument including a shell and a pair of vibratory heads oppositely disposed relative to said shell, said means including a pair of damper elements within said instrument for each of said heads, a cross-member fixedly linking together each pair of damper elements, an elongated resilient member positioned at right angles to and connected at one end to each of said cross-members, means connecting the other ends of said resilient members to said shell, an external control mounted on said shell, and a linkage from said external control to both resilient members for simultaneously controlling whether both pairs of damper elements exert pressure upon said vibratory heads or are spaced therefrom, said linkage including idler rollers mounted on said cross members and cords on said rollers connected at one end to said external control, and another external control mounted on said shell and means linking said last control to the other ends of said cords for controlling both resilient members and the degree of pressure said damper elements exert upon said heads.

2. A percussion musical instrument provided with means for masking overtones to any desired extent, said instrument including a shell and a pair of vibratory heads oppositely disposed relative to said shell, said means also including a pair of rubber damper cups within said instrument for each of said heads, a pair of cross-members also within said instrument and rigidly secured respectively to each pair of cups, a resilient member positioned at right angles and fastened near each end to each cross-member at substantially the center thereof, means fastening the other ends of said resilient members to said shell, a member mounted externally of said shell, and cords within said instrument linking said external member to spaced points on both resilient members for simultaneously controlling whether both pairs of damper cups exert pressure upon said vibratory heads or are spaced therefrom, and another member mounted externally of said shell and also linked to said resilient members at said spaced points for controlling the degree of pressure which said damper cups exert upon said vibratory heads.

WILLIAM D. GLADSTONE.
